CLAIM

The ornamental design for a LED track module with rectangular aperture, as shown and described.

DESCRIPTION

FIG. 1 is a top right perspective view of the LED track module with rectangular aperture showing my new design;

FIG. 2 is a front elevational view;

FIG. 3 is a rear elevational view;

FIG. 4 is a left side elevational view, with the unshown right side elevational view being a mirror image thereof;

FIG. 5 is a top plan view; and,

FIG. 6 is a bottom plan view.

In the drawings the broken line showings depict environmental subject matter and form no parts of the claim.
